Term of patent 14 years

(Cl. D18—2)

FIG. 1

FIG. 2

FIG. 3

FIG. 1 is a front face view of a tile showing our new design.

FIG. 2 is a front face view of a tile showing a modification of our new design.

FIG. 3 is an enlarged fragmentary view taken substantially on line 3-3 of FIG. 2.

In FIG. 1 the tile is shown as consisting of a background of one color over printed with a contrasting color. In FIG. 2 the design of FIG. 1 is shown with the addition of a number of small round dots representing holes punched into the porous body of the fiber board and the coating thereon, such holes being shown in FIG. 3.

We claim:

The ornamental design for a ceiling tile or similar article, substantially as shown and described.
